INHALANT HOOD

John A. Blosser, Oakland, Calif.

Application July 12, 1943, Serial No. 494,323

8 Claims. (Cl. 128—140)

The invention relates to a head-receiving hood or tent designed for use in administering an inhalant to a reclining person.

A general object of the invention is to provide a particularly simple and compact and inexpensive hood for the administration of oxygen and other inhalants in gas therapy treatments and the like.

Another object is to provide a portable and folding hood structure which is adapted for field use in times of war or public calamity, as well as in hospital and other buildings.

A further object is to provide a hood of the class described having its members inseparably associated and arranged for cooperation to provide a form-retaining hood or for their mutual folding together in a compact and flat package.

Yet another object is to provide a hood of the character described having transparent side walls to permit an observation of the person being treated within it.

An added object is to provide an improved hood structure which is arranged for setting up as a tent about the head of a positioned patient.

The invention possesses other objects and features of invention, some of which, with the foregoing, will be set forth or be apparent in the following description of a typical embodiment of the invention, and in the accompanying drawings, in which,

Figure 1 is a perspective view of a set-up hood embodying the features of present invention.

Figure 2 is a side elevation showing the hood in use with a patient on a bed.

Figure 3 is an enlarged fragmentary axial section of a gas inlet connection for the hood.

Figure 4 is a top view of the set-up hood.

Figure 5 is a sectional elevation of the hood at the line 5—5 in Figure 4.

Figure 6 is an enlarged fragmentary section taken at the line 6—6 in Figure 4.

Figure 7 shows the hood folded or packaged for its transportation or storage.

Figure 8 is an end view of the folded-up hood unit.

Figure 9 shows the hood structure opened out flat as a blank.

In general terms, the disclosed hood-forming structure 11 embodying my invention comprises a quadrilateral base member 12, side wall members 13 and 14 hingedly attached to opposite side edges of the base 12, a wall member 15 hingedly attached to one end of the base 12, and cooperative means on the wall members for releasably and mutually securing them in hood-

forming relation. As shown in Figure 2, the set-up hood is arranged to receive the head of a patient P disposed above the base member 12 and having his body extending from the opposite end of the hood from the end wall member 15, the latter comprising a head-end, or head wall, member of the hood.

In the present embodiment of my invention, the base member 12 is an isosceles trapezoid in outline, and has the side wall members 13 and 14 hingedly attached to it at and along its side edges. The head wall member 15 is also an isosceles trapezoid in outline, and this member has its longer base edge attached to the base member 12 at and along the shorter base edge of the latter, said edges being of like length. The wall members 13 and 14 comprise pieces of a normally flat and elastically flexible sheet material which may be, and is preferably, transparent for permitting a viewing therethrough of the contents of the space within the set-up hood. The head wall member comprises a piece of flat sheet material which may be the same as that of the side wall members 13 and 14, though the elastically flexible and transparent qualities of the members 13 and 14 are not essential in the wall 15. A particularly satisfactory material for the wall members 13 and 14 and 15 has been found to comprise cellulosic sheet material such as the film on which X-ray pictures are taken.

The disclosed base member 12 is quadrilateral in outline and is formed of a more-or-less flexible and relatively heavy fabric such as canvas, and edge extensions 16 and 17 and 18 thereof are fixed to and flat against the inner faces of the adjacent edge portions of the wall members 13 and 14 and 15 respectively as by the use of an adhesive and/or stitching 19, as is brought out in Figure 9. This manner of attaching the hood walls to the base 12 is understood to provide hinged connections for the hood elements, with the axes of hinging at the edge lines of the wall members in the planes of their inner faces, it being noted that these continuous hinge connections are gas-tight under atmospheric pressure conditions, as is desirable.

It will now be noted that the edges 21 at the head ends of the side wall members 13 and 14 have the same lengths as the side edges 22 of the head wall member 15, and that the edges 21 are coterminous with the edges 22 at the head-end corners of the base 12; accordingly, the first said wall edges 21 may be brought into line registration with the corresponding second said wall edges 22 by appropriately disposing the side and

head walls to extend upwardly above the common plane of their axes of hinging. In the present structure, the head end edges 21 of the side walls 13 and 14 are perpendicular to the axes of hinging of the members whereby said edges will register with the side edges 22 of the head wall 15 when the latter wall is perpendicular to said common plane of hinging of the walls, the particular relation being brought out in Figure 2. The head wall 15 is not, however, necessarily perpendicular to the common plane of hinging of the walls when its side edges register with the head end edges 21 of the side walls, it being understood that the angularity of the edges 21 to the axes of hinging of the side walls and/or the angularity of the edges 21 to the axis of hinging of the head wall may be varied somewhat to define a gas-tight head end for the hood cavity.

The means provided for mutually securing the side walls 13 and 14 and head wall 15 is preferably releasable for permitting a compact folding of the hood assembly when not in use and the erection of the hood about a patient's head. A particularly simple means for the purpose comprises strips of adhesive tape applied over and along the outside corners at the lines of abutment of the edges 21 of the side walls with the side edges 22 of the head wall, but this manner of securing the erected walls together has been found to have the disadvantage that the two tape strips required must be provided as separate elements and may not be available when needed. It is therefore generally preferable that the releasable wall connection means at the registered edges 21 and 22 be provided on and as part of the walls for insuring their constant availability, and such a means is particularly disclosed as comprising a slide fastener connection of a well-known type.

As shown, the mutual connections for registering wall edges 21 and 22 are provided by lines of hooks 23 mounted on the different edges and cooperative in mutually staggered and aligned relation to fix the edges together, the connection being progressively effected or released by means of a slide or runner element 24 engaging both lines of hooks 23. When the runners 24 are nearest the points of intersection of the edges 21 and 22, as in Figure 9, the corresponding wall members are free for independent swinging to their folded positions indicated in Figure 7, and when the runners are at the outer ends of said edges, the wall edges are fixed together along their lengths to provide the outside hood corners previously referred to. It has been found that the closed corner joints so provided are substantially sealed or gas-tight for present purposes under the atmospheric pressure conditions of use of the hood.

It will now be noted that the present hood assembly is constructed for its erection to provide a hood space about the head and adjacent body portion of a person P initially supported upon the hood base 12. A bed mattress M, or other support as the ground, may supportingly underlie the base 12, with the pliability of the base permitting its general conformation to the surface of support provided beneath it. The base 12 may readily be disposed beneath a patient's head with a minimum of disturbance of the patient, as is frequently imperative, and while the assembly is laid out flat as in Figure 9.

When the base 12 has been appropriately disposed beneath the patient's head, the side and head walls of the hood assembly are elevated into engagement along their edges 21 and 22, and are secured together by the described slide fastener,

or other, means, and the side wall members 13 and 14 are then flexedly distorted out of their normal flat form into overlapped engagement over the part of the patient's body upon the base with the portions thereof adjacent their foot edges 25 and 26 respectively arched against the body to jointly seal the foot end portion of the hood cavity thereat, means being provided to releasably secure the flexed side walls in the latter position. If the patient is an adult, as is particularly indicated, the present hood structure would engage the chest of the patient. If a child uses the hood, more of its body would lie within the hood space, while all of an infant's body might be disposed within the hood.

As particularly shown, the side wall members 13 and 14 are provided with flexible tie straps 27 and 28 of leather or fabric and respectively extending from their free side edges 29 and 30 in general alignment with their end edges 25 and 26 respectively. In the present assembly, the wall member 13 is arranged to overlap the wall member 14 in their cooperative relation to provide the top of the hood cavity, it being understood that the elasticity of the members maintains them in flat surface engagement at their opposed face areas. The wall member 13 is provided with a slot 32 adjacent and generally parallel to its axis of hinging to the base 12 and for receiving the tie strap 28 of the underlying wall member 14 therethrough, and when the desired shaping and disposition of the side wall members has been effected, the ends of the straps 27 and 28 are secured for maintaining the hood in its operative relation to the patient's body; in the present case, the strap ends are tucked beneath the base and patient for the purpose of securing them.

When the present hood unit is set up as shown and described, the top edge 33 of the head wall member 15 is cooperative with the adjacent portions of the side edges 29 and 30 of the side wall members 13 and 14 respectively to define a generally triangular opening 34 at the top of the structure, said opening serving for the venting of vitiated air from the hood. Owing to the elastic flexibility of the side wall members 13 and 14, the side edges 29 and 30 thereof may be in different angular relations independently of the fitting of the hood to the patient's body and so cooperate with the top edge 33 of the head wall 15 to define triangular top openings 34 of different areas. Means are accordingly provided for securing the members 13 and 14 in a plurality of adjusted relations at the opening 34, said means being disclosed as comprising plural spring-snap connections between the members adjacent the opening.

As particularly shown, inwardly opening spring socket members 35 are provided on the wall member 13 in a line adjacent and parallel with the edge 29 thereof, while a corresponding line of outwardly projecting plugs 36 for snap-in engagement in the sockets 35 is provided on the wall member 14 adjacent and parallel with the edge 30 thereof; the arrangement is such that different plugs 36 may be engaged in corresponding socket members 35 to fix the wall edges 29 and 30 in different angular relation between the head wall member 15 and the apex of the generally isosceles triangle which they define, and so provide a vent opening 34 of adjusted size. With the present base member thirty inches long and twenty-four inches wide at its head end and thirty inches wide at its foot end, and the head-wall member eighteen inches long and six inches wide at its top edge 33, it has been found in practice that

the area of the hood opening 34 should be adjustable between fifteen and twenty-five square inches for meeting normal requirements for patients of different sizes and/or conditions for treatment.

The present hood is particularly valuable for the administration of oxygen for supporting respiration, though usable for the administration of other gases or gaseous mixtures. Accordingly, and as brought out in Figures 2 and 3, a gas inlet port 37 is provided through the head wall member 15 adjacent its bottom for the connection of a gas supply tube 38 thereat by means of a suitable connector 39. As particularly shown, the connector 39 comprises a tubular stem 41 engaged in the discharge end of the tube and providing a radial flange 42 at the rear end of a threaded forward end portion 41' thereof, said stem portion being extendable through the port 37 and threadedly mounting a clamp nut or ring 43 at the opposite side of the member 15 from the flange for clamping the member between it and the flange, and so sealedly and detachably mounting the connector 39 on the member. Oxygen is supplied to the tube and hood at a controlled rate through an adjustable needle valve 44 and from a suitable source such as a tank 45 of the compressed gas. The discharge end of the supply tube 44, might, of course, be extended into the hood space through the opening provided beside the patient's body, the provision and use of the port 37 then being dispensed with. In either case, the inhalant would be introduced below the level of the patient's nose and face.

Owing to the fact that the gaseous mixture exhaled by the patient is warmer, and therefore lighter, than the surrounding gases in the hood space, it tends to rise through said space to escape at the top opening 34. Also, the warming of the gases in the hood space by the heat radiated from the enclosed portion of the patient's body tends to create a convection rise of the gases. Then too, the introduced oxygen tends to stay at the bottom of the hood space by reason of its greater specific gravity while displacing the other gases upwardly in said space by reason of its inflow and thereby supplement the foregoing convection effects for creating an upward flow of the gases through and from the hood at the outlet opening 34.

Recalling that the connections of the base member with the various wall members provides a gas-tight seal for the bottom of the hood cavity, it will be understood that the permitted rate of upward flow of gases through the hood space is jointly determined by the adjusted rate of introduction of oxygen into said space, by the rate of any inward air leakage about the patient's body at the foot-end side wall edges 25 and 26, by the rate of any inward air leakage through the slide-fastener or other wall connections at the sides of the head wall 15, and by the adjusted size of the discharge opening 34. Any air inflow into the hood space from the foot end of the hood along the patient's body may be readily regulated in accordance with the adjusted fit of the hood side walls over the body and/or the application of a loose cover member (not shown) thereat, it being obvious that the permitted inflow of air at any air-inlet point should, in the interest of the economical use of the oxygen, prevent the escape of oxygen from the hood at that point.

In view of the foregoing, it will be understood that the effective rate of supply and the oxy-

gen content of the gaseous mixture made available to the patient for inhalation is readily controlled by adjustably and controllably varying the permitted rate of air inlet about the patient's body and/or the oxygen content of the gas admitted through the hose connector 39 and/or the rate of introduction of oxygen and/or the area of the vent opening 34. It will also be understood that the heat and moisture given off by the enclosed portion of the patient's body and in the exhalations of the patient may comprise the sole sources of heat and moisture within and determining the actual temperature and humidity within the hood in accordance with the adjusted flow rate of gases permitted therethrough. Accessory apparatus for testing and/or controlling the temperature and humidity may, of course, be provided.

The folding feature of the present hood structure makes the same particularly valuable as part of the equipment of mobile or fixed field hospitals or first-aid centers. By reference to Figures 6 and 7 and 8, it will be noted that the quadrilateral wall members 13 and 14 and 15 are all so shaped that they may be folded and lapped into positions opposite the base 12 without extending laterally beyond the base, whereby the flat-folded or packaged hood is no larger in its plane than the base. Having a side wall member outermost with respect to the base wall member, its tie strap may be looped around the package for tying up the same; as shown in Figures 7 and 8, the wall member 13 is outermost and its strap 27 is so utilized.

While the present hood has been hereinbefore particularly described as used for the administering of oxygen as an inhalant at atmospheric pressure, it will be understood that inhalants other than oxygen may be administered therewith; for instance, gaseous anesthetics and/or medicaments may be administered within the present hood structure. Furthermore, since the present hood structure is a unit with all parts attached and is usable without any accessory equipment other than a source of gas and a hose therefrom, it is particularly useful as emergency and field hospital equipment.

From the foregoing description taken in connection with the accompanying drawings, the advantages of the construction and use of the present hood for administering inhalants will be readily understood by those skilled in the art to which this invention appertains. While I have described the features and principles of use of an assembly which I now consider to comprise a preferred embodiment of my invention, I desire to have it understood that the showing is primarily illustrative, and that such changes may be made, when desired, as fall within the scope of the following claims:

1. In an inhalant hood, a quadrilateral base member arranged for the supported disposal of the head portion of a person's body longitudinally thereover to extend from the foot end thereof, a flat head-wall member extending upwardly from the head end of the base member, normally flat side-wall members of resiliently elastic sheet material extending along and upwardly from the sides of the base member, said side wall members having their head ends sealedly connected to and along the sides of the head-wall member and being flexed into mutually lapped relation over said head portion of the person's body to provide a generally fitted engagement of their foot ends therewith whereby the base and head and side

members are cooperative to define a space enclosing said head portion of the person's body, said space being effectively gas-tight at its sides and bottom and having a top opening defined by the upper edges of the head and side wall members.

2. A structure in accordance with claim 1 having means releasably securing the side wall members in said flexed and mutually lapped relation.

3. A structure in accordance with claim 1 having means releasably securing the side and head wall members together at head-end corners of the hood, and other means releasably securing the side wall members in said flexed and mutually lapped cooperative relation.

4. A structure in accordance with claim 1 having means releasably securing the side and head wall members together at head-end corners of the hood, other means releasably securing the side wall members in said flexed and mutually lapped relation, and means unitarily hinging the head and side wall members to the base member in such manner that the mutually freed said wall members may be disposed to extend laterally from the base member or be folded inwardly upon the base member, optionally.

5. In an inhalant hood, a quadrilateral base member arranged for the supported disposal of the head portion of a person's body longitudinally thereover to extend from the foot end thereof, a quadrilateral head wall member of stiff sheet material hingedly connected to the sides of the base member by a gas-tight hinge means and extending between the head-end corners of the base member, quadrilateral side wall members of elastically flexible and normally flat sheet material hingedly connected to the sides of the base member by a gas-tight hinge means and extending from the corresponding head-end corners of the base member and having their head-end edges arranged for registration with the different side edges of the head member, releasable means on and cooperative between the registered said edges of the members for providing gas-tight connections therealong, and strap members extending from the free foot-end corners of the side wall members for securing the latter members in mutually lapped and flexed relation with their foot-end portions engaged over and against the body of the person when the members are secured to the head end members by the aforesaid means provided therefor.

6. In an inhalant hood unit, a quadrilateral base member arranged for the supported disposal of the head portion of a person's body longitudinally thereover to extend from the foot end thereof, a quadrilateral head member of stiff sheet material hingedly connected to the head

end of the base member by a gas-tight hinge means and extending between the head-end corners of the base member and arranged for folded disposal opposite the base member, quadrilateral

- 5 side wall members of elastically flexible sheet material hingedly connected to the sides of the base member by a gas-tight hinge means and extending from the corresponding head-end corners of the base member and arranged for folded disposal opposite the base member or for their disposal to have their head-end edges in registration with the different side edges of the head member, means cooperative between the registered edges of the head and side members for 10 providing releasable gas-tight connections therealong, and tie members extending from the side members for use in securing these members in mutually lapped relation and flexed condition with their foot-end portions engaged over and 20 against the body of the patient when the edge connecting means is operative or for use in securing the hood in folded-up condition.

7. In an inhalant hood unit, a base member having its edges defining a straight-sided area 25 for the supported disposal of a head portion of a person's body longitudinally thereover, a head wall member hingedly attached to and extending along and laterally from the head end of the base member, side wall members of elastically 30 flexible and normally flat sheet material hingedly attached to and extending longitudinally along and laterally from the side edges of the base member and having their head-end edges arranged for complementary registration with corresponding side edges of the head wall member 35 when the members are extended upwardly from the base member, means operative at the mutually registerable edges of the head wall member and side wall members to releasably and sealedly 40 secure said members together when their said complementary edges are in registration, and means cooperative between the side wall members at their foot-end portions for releasably securing the latter members in mutually lapped and cylindrically flexed condition opposite the foot end portion of the base area.

8. A structure in accordance with claim 7 whereof the head wall member is of trapezoidal form having its shorter base at its free edge, and the side wall members are quadrilateral and are provided with means directly cooperative therebetween at points adjacent the side edges thereof which extend from the outer ends of their head-end edges to secure the members in adjustably lapped relation therat independently of the securing means at their foot-end portions.

JOHN A. BLOSSER.
